United States Patent Office

Des. 179,486
Patented Jan. 1, 1957

179,486

SHOE

Beth Levine, New York, N. Y.

Application April 10, 1956, Serial No. 40,996

Term of patent 14 years

(Cl. D7—7)

FIG. 1.

FIG. 2.

FIG. 3.

I claim:

The ornamental design for a shoe, substantially as shown.
